COMBINED BRUSH AND SPONGE FOR SURGICAL SCRUBBING OR THE LIKE

Jack W. Kaufman, 357 Frankel Blvd.,
Merrick, N.Y. 11566

Continuation-in-part of design application Ser. No.
355,741, Apr. 30, 1973. This application July 25,
1974, Ser. No. 491,764

Term of patent 14 years

Int. Cl. D4—02

U.S. Cl. D4—17

FIG. 1 is a perspective view of a combined brush and sponge for surgical scrubbing or the like, showing my new design;

FIG. 2 is an end elevational view thereof;

FIG. 3 is an end elevational view of a modified form thereof shown fragmentarily for ease of illustration;

FIG. 4 is an end elevational view of a further modified form thereof shown fragmentarily for ease of illustration; and

FIG. 5 is a sectional view along the line 5—5 of FIG. 2.

The broken line disclosure in FIG. 2 has been included to clearly illustrate the manner in which the claimed article is utilized and forms no part of the claimed design.

The ends not shown in the modifications of FIGS. 3 and 4 are substantially identical in appearance to those which are shown.

This is a continuation-in-part of design application Ser. No. 355,741, filed Apr. 30, 1973.

I claim:

The ornamental design for a combined brush and sponge for surgical scrubbing or the like, substantially as shown and described.
